(57) **CLAIM**

We claim the ornamental design for a lighting fixture, as shown and described.

DESCRIPTION

FIG. 1 is a left elevation view showing a first embodiment of my new design of a lighting fixture;
FIG. 2 is a right elevation view of the lighting fixture of the first embodiment;
FIG. 3 is a front elevation view of the lighting fixture of the first embodiment;
FIG. 4 is a rear elevation view of the lighting fixture of the first embodiment;
FIG. 5 is a top plan view of the lighting fixture of the first embodiment;
FIG. 6 is a bottom view of the lighting fixture of the first embodiment;
FIG. 7 is a perspective view of the lighting fixture of the first embodiment;
FIG. 8 is a left elevation view showing a second embodiment of my new design of a lighting fixture;
FIG. 9 is a right elevation view of the lighting fixture of the second embodiment;
FIG. 10 is a front elevation view of the lighting fixture of the second embodiment;
FIG. 11 is a rear elevation view of the lighting fixture of the second embodiment;
FIG. 12 is a top plan view of the lighting fixture of the second embodiment;
FIG. 13 is a bottom view of the lighting fixture of the second embodiment;
FIG. 14 is a perspective view of the lighting fixture of the second embodiment;
FIG. 15 is a left elevation view showing a third embodiment of my new design of a lighting fixture;
FIG. 16 is a right elevation view of the lighting fixture of the third embodiment;
FIG. 17 is a front elevation view of the lighting fixture of the third embodiment;
FIG. 18 is a rear elevation view of the lighting fixture of the third embodiment;
FIG. 19 is a top plan view of the lighting fixture of the third embodiment;
FIG. 20 is a bottom view of the lighting fixture of the third embodiment; and,
FIG. 21 is a perspective view of the lighting fixture of the third embodiment.
